Leigh G. Hurd.

UNITED STATES PATENT OFFICE.

LEIGH G. HURD, OF LOS ANGELES, CALIFORNIA.

HATPIN-FASTENER.

1,368,154.

Specification of Letters Patent. Patented Feb. 8, 1921.

Application filed August 30, 1920. Serial No. 406,792.

To all whom it may concern:

Be it known that I, LEIGH G. HURD, a citizen of the United States, residing at Los Angeles, in the county of Los Angeles and 5 State of California, have invented new and useful Improvements in Hatpin-Fasteners, of which the following is a specification.

My invention relates to improvements in 10 hat-pin fasteners and particularly in a device that can be attached to the ordinary hat-pin and which will prevent the loss of same.

It is the object of this invention to provide 15 a hat-pin fastener that can be readily attached to or detached from the ordinary hat-pins in common use.

Another object is to provide a hat-pin fastener that can be attached to the outside of the hat crown and worn as an ornament, or 20 if so desired it can be attached inside of the hat crown and therefore be invisible from an outside view.

A further object of this invention is to provide a hat-pin fastener that is simple in 25 construction and that can be cheaply manufactured.

Other objects will appear hereinafter.

My invention is illustrated in the accompanying drawing, in which:

30 Figure 1, is a side elevational view of the fastener attached to an ordinary hat-pin, and is the preferred form of my invention. Fig. 2, is an end elevational view of thin inside plate. Fig. 3, is an end elevational view 35 of outside plate with radius. Fig. 4, is a perspective view of the thin inside plate. Fig. 5, is a perspective view of the outside plate showing wires or prongs for attaching the fastener to the hat. Fig. 6, is an end elevational view of the fastener when both 40 plates are in register, as when they are attached to the hat. Fig. 7, is a modified form of my invention in open position for receiving hatpin. Fig. 8, is an end elevational 45 view of the same device in closed position.

Similar numerals refer to similar parts throughout the several views. More specifically the plates 4 and 5 are formed with central elongated openings 8 and 9, and when 50 plates 4 and 5 are in register as shown in Figs. 1 and 6 form a circular orifice or opening which slidably supports the hat-pin shank 2, which has previously been formed with a flattened end adjacent to its point, as 55 shown at 3 in Fig. 1.

Referring to the drawings: Fig. 1 shows the preferred form of my fastener attached to an ordinary hat-pin which has a slightly flattened end adjacent to its point. Any ordinary hat-pin can be used with my fasteners, as all that is necessary is to slightly flatten the end as shown at 3 in Fig. 1. In the operation of the fastener shown in Figs. 1, 2, 3, 4, 5 and 6, a hat-pin which has a slightly flattened end 3 and a head 7, is inserted in the elongated aperture 8, as shown in Figs. 3 and 5. After inserting the pin through the aperture 8 in plate 5, the flattened end of the hat-pin is inserted through the elongated aperture 9 in the thin plate 4, 60 shown in Figs. 2 and 4. The plates 4 and 5 are now pressed together so that the wires or prongs 6 will protrude through the openings 10 in plate 4, care being taken to see that the elongated apertures 8 and 9 are in correct position to form a circular orifice in the center of the fastener as shown in Fig. 6, at 65 A. When the plates are pressed together, the hat-pin and fastener are ready to be inserted in the hat, as shown in Fig. 1. All 70 that is necessary to attach the hat-pin and fastener to a hat, is to insert the hat-pin at the desired point in the hat crown and push the wires or prongs 6 through the hat also, 75 when the wires can be bent over inside of the 75 hat to hold the hat-pin and fastener against removal. When attached to a hat, a hat-pin equipped with this fastener is used the same as any other. It will here be noted that the 80 hat-pin with a flattened end adjacent to its 85 point can easily be removed from the plates 4 and 5 when they are apart, but that this is impossible when the plates are together and 90 in register as shown in Fig. 1. If it is desired to have the fastener invisible and not 95 show on the outside of the hat, all that is necessary, is to insert the hat-pin with the flattened end, in the hat crown previous to attaching the fastener to the hat-pin as follows:—

100 Insert the hat-pin with the flattened end at the desired point in the hat crown and then insert the hat-pin in the fastener inside of the hat, attaching the hat-pin to the device in the opposite position shown in Fig. 1. 105 In this position the wires or prongs 6 would be pushed through the hat crown from the inside of the hat and would therefore be bent over on the outside of the hat to hold the fastener and hat-pin in place. 110

In the modified form of my invention shown in Figs. 7 and 8, two plates 11 and 12 are pivoted together as shown at 14. These two plates 11 and 12 having elongated openings 17 and 18, through which the hat-pin shank 2 with the flattened end 3 adjacent to its point, as shown in Fig. 1, may pass, as shown in Fig. 7, at 17 and 18. Plate 12 is equipped with a small pin 16, which fits 10 into an orifice 15 in the plate 11, when the device is in closed position as shown in Fig. 8.

When plates 11 and 12 are in closed position or in register as shown in Fig. 8, a hat-pin with a flattened end adjacent to its point which has previously been inserted in the fastener when it was in open position as shown in Fig. 7, cannot be withdrawn, as the flattened end of the hat-pin prevents this as can readily be seen. The style of fastener shown in Figs. 7 and 8 is intended mainly for use inside of the hat, and is attached to the hat by means being inserted through the openings 13. In the operation 20 of this fastener it is first attached to the inside of the hat, although it can be used on the outside of the hat if desired. The plate 12 being made from thin spring metal is pushed away from the plate 11 so that 25 the short pin 16 will release from the opening 15 in the plate 11. After releasing, plate 12 is swung open on its pivot 14. The hat-

pin with the flattened end adjacent to its point, is now thrust through the elongated openings 17 and 18. The plate 12 is then 35 pushed back until the pin 16 snaps into the opening 15 in the plate 11, which prevents the withdrawal of the hat-pin, the fastener being in register as shown in Fig. 8.

Having thus described my invention, what 40 I claim is:

A hat-pin fastener comprising the combination of a hat-pin having a pointed shank formed with a flattened and broadened end adjacent to the point, and two members having elongated openings through which the flattened and broadened end of the hat-pin can pass when the members are apart or not 45 in register, but when said members are together and in register forms a circular opening which slidably encircles and fits the hat-pin shank, but of such a diameter that the flattened and broadened end of the hat-pin cannot pass therethrough, and projecting 50 means attached to one of the members which fit into openings in the second member, holding both members in positive register when attached to the shank of a hat-pin, and means for detachably attaching said fastener and a hat-pin to a hat. 55

In testimony whereof I have signed my name to this specification.

LEIGH G. HURD.
